UNITED STATES PATENT OFFICE.

GEORGE L. HARVEY, OF CHICAGO, ILLINOIS.

DUMPING-VEHICLE.

1,294,799.

Specification of Letters Patent. Patented Feb. 18, 1919.

Application filed July 16, 1918. Serial No. 245,226.

To all whom it may concern:

Be it known that I, GEORGE L. HARVEY, a citizen of the United States, resident of Chicago, in the county of Cook and State of Illinois, have invented certain new and useful Improvements in Dumping-Vehicles, of which the following is a specification.

My invention relates to a dumping vehicle and particularly to an improvement on the device shown in my co-pending application, Serial No. 237,852, filed June 3, 1918.

One of the objections to some or all of the elevating and tilting devices heretofore designed is that of instability while in such position. In many of the devices at present in use great care must be exercised to avoid the tendency of the elevated body and its load to over-balance the forward end of the vehicle and over-turn backward. This possibility arises from the fact that when elevated, a vertical line through the center of gravity of the load falls dangerously near to the rear axle and if the burden is unevenly distributed, either in loading or discharging, such an accident is likely to occur. It may also occur if the vehicle is backed against a curb while the body is elevated or while stationary if the vehicle is in a backwardly inclined position.

This difficulty is avoided in the present construction by so arranging the parts that the body is first raised horizontally to substantially its full height and then tilted, the forward or tilting end being raised in substantially a vertical line. In effect the body is carried bodily forward and in final elevated tilting position the center of gravity of the load falls at a point no farther to the rear than when the body is in normal lowered position.

Another advantage in the present construction is in that the body may be elevated to substantially its full height with the body in a horizontal position. This has many advantages which will readily be understood; it enables side instead of end discharge and provides for delivery of the load at elevated points as when icing refrigerator cars.

A further advantage is in the fact that the lift by means of which the body is elevated and tilted is in substantially a straight line. In all devices in which the body is oscillated about a fixed pivot at the rear of the vehicle, the front end must necessarily move in the arc of a circle and this serves to carry the forward end a considerable distance to

the rear. Consequently the lifting force must be exerted at a material angle in the elevated positions. This increases the force necessary to be applied and requires stronger and heavier parts to withstand such force. In my construction the lifting force is applied in substantially a vertical line.

The invention will be more readily understood by reference to the accompanying drawings, wherein,

Fig. 1 is a plan view of a dumping vehicle frame constructed in accordance with my invention;

Fig. 2 is an elevation thereof showing the body in full lines in an elevated substantially horizontal position and in dotted lines in an extreme elevated and tilted position;

Fig. 3 is a view showing the body in an extreme tilted but not elevated position;

Fig. 4 is a view showing a tilted and somewhat elevated position;

Fig. 5 is a view showing the tilted and less elevated position;

Fig. 6 is a sectional view taken on the line 6—6 of Fig. 7;

Fig. 7 is a sectional view on the line 7—7 of Fig. 6;

Fig. 8 is a sectional view on the line 8—8 of Fig. 7;

Fig. 9 is a fragmentary end elevation, and,

Fig. 10 is a sectional view showing means for applying an elevating force.

In the drawings the device is shown as applied to a vehicle such as a motor truck, the same being provided with a main frame 10, of the usual form. Superposed on the main frame is a body frame 11, which serves to support any suitable body 12. As a means for elevating and tilting the body I provide the beams 13, 14, the beam 13, consisting of two parallel members joined by suitable cross pieces 15, and the beam 14, likewise consisting of two parallel members joined by the cross members 16. The beams 13, 14, are pivoted at 17 and 18, respectively to the body frame. The beams extend in opposite directions and have a sliding bearing, one on the main frame 10, and the other on a third beam 19, which in normal operation forms a part of the main frame. The beam 13, which has a bearing on the main frame, is provided with rollers 20, as best shown in Figs. 2, 8 and 9, these rollers in certain positions of the parts engaging stops 21, fixed to the rear of the main frame. In another

position the rollers engage stops 22, at a point forward of the stops 21. In other words, the rear end of the beam 13, is adapted to move on its rollers between the 5 stops as required in the subsequently described operations.

The beam 14, has a sliding engagement, as best shown in Fig. 2, with the beam 19, anti-friction rollers 23, on the beam 14, en-10 gaging the underside of the beam 19, and being adapted to reciprocate between stops 24, 25, on the beam 19.

At the intersection of the beams 13, 14, I provide a fulcrum consisting of the stirrups 15 26, through which the two members of the beam 13, extend, anti-friction rolls 27, 28, being provided above and below the beam members, as best shown in Fig. 6, the stirrups adapted for oscillation on a transverse 20 shaft 29, which has a bearing in a casting 30, this casting engaging the two sides of the two members constituting the beam 14. The casting is engaged by a long threaded shaft 31, as best shown in Fig. 7, the shaft ex-25 tending to the end of the frame and being adapted to be engaged by a crank 32, whereby it may be rotated. In this manner the fulcrum member may be reciprocated and located at different points as required in 30 order to control the height or extent of elevation of the body.

In order to operate the device as a straight tilting body, the beam 19, is pivoted at its rear end in the bracket 33, the same being 25 normally retained in the position shown in Fig. 2, by means of the loop 34, or other suitable means. If the body is to be tilted and not elevated the loop 34, is disengaged from the forward end of the beam 19, and 40 upon elevation the parts assume the position shown in Fig. 3.

As a means for elevating the body I provide the cylinder 35, to which a pipe 36, may be connected, as best shown in Fig. 10. A 45 piston 37, operating within the cylinder, acts through the agency of the cables 38, engaging suitable arms 39, to lift the forward end of the body. One of the objects, as heretofore explained, is to so arrange the parts 50 that the lifting shall be in substantially a vertical line. That this is accomplished is illustrated in the full and dotted line positions of Fig. 2. It will be seen from that figure that the lifting force is supplied in 55 substantially a line parallel to the piston rod constituting the lifting element.

One of the important advantages arising from the use of this construction is that the body is elevated to substantially its full 60 height while in a horizontal position. The first action following the application of a lifting force to the forward end of the body is to cause the travel of the beam 14, between the stops 24, 25. As the body is ele-65 vated the free end of the beam 13, remains

stationary and the beam oscillates about the roller 20, as a pivot. However, the beam 14, not only oscillates about the roller 23, as a pivot, but it also travels rearwardly. However, after reaching the full line position of Fig. 2, that is, a point where the roller 23, contacts the stop 25, the roller 20, then begins to travel forwardly toward the stop 22, and the body is tilted accordingly. It will be seen, however, that the body does 75 not during the tilting movement, move rearwardly but in effect its forward end travels in almost a vertical line. Thus there is no tendency toward upsetting the vehicle by moving the center of gravity of the load to 80 the rear of the rear axle. In its final completely elevated and tilting position it will be seen that the body occupies a position substantially in line with that which it occupies when in its lowered position. The different 85 positions which may be secured by changing the position of the fulcrum at the intersection of the beams 13, 14, are illustrated in Figs. 2, 4 and 5. By adjusting this fulcrum any desired height of dump may be 90 secured. When the fulcrum is at its extreme forward position the body may be elevated to substantially its extreme height and still remain in a horizontal position. This is of 95 material advantage when it is desired to dump from the side or to deliver the contents of the load onto an elevated platform.

In the accompanying claims the beam 14, is referred to as the elevating beam and the beam 13, as the elevating and tilting beam; 100 this for the reason that the beam 14, has only the function of elevating the body while the beam 13, has the combined function of elevating the body until the sliding end of the beam 14, contacts its stop and thereafter 105 as a tilting beam, the tilting continuing until the free end of the beam 13, contacts the stop 22.

Of course, the extent of bodily horizontal elevation is varied by the position of the fulcrum at the intersection of the beams and the different positions as to the extent of elevation and tilting are secured by adjusting this fulcrum. Claims directed to the adjustable fulcrum have been made in my co-pending application heretofore referred to and therefore the same is not broadly claimed herein. It is possible that the result secured by the use of the apparatus herein described might be secured by the use of a 110 somewhat different arrangement and I do not wish to be limited other than as indicated in the appended claims, the usual advantage arising from the use of mechanical equivalents being afforded. I am unconvinced that a similar result could not be secured by causing the elevating beam to slide on the body instead of on the support. The important feature from a practical stand-point is that a vertical line through the cen- 115 120 125 130

ter of gravity of the load should remain at substantially the same point during the elevating and tilting actions.

I claim:

5. 1. In a body dumping device, the combination of a supporting frame, a body, a pair of oppositely extending beams, one end of each beam being pivoted to the front and rear respectively of the body, a sliding fulcrum at the intersection of said beams, the free ends of said beams having the capacity for limited sliding movement relative to the supporting frame, the arrangement being such that on the application of 15 a lifting force to the body, the body is elevated substantially horizontally and then tilted, substantially as described.

2. In a vehicle body dumping device, the combination with the body of an elevating beam and an elevating and tilting beam pivoted to the rear and front portions respectively of the body, the elevating beam having sliding engagement with a support, a stop for limiting the extent of sliding engagement, the elevating and tilting beam also having sliding engagement with a support between limiting stops, and means at the intersection of the beams for controlling the sliding movement of the free ends of the 30 beams, the arrangement being such that the first effect of a lifting force applied to the body is to cause both beams to act as elevating devices, no substantial tilting action being secured until the elevating beam contacts its stop, substantially as described.

3. In a body dumping vehicle, the combination of a main frame, a body, a pair of oppositely extending beams pivoted to the front and rear ends respectively of the body, a third beam pivoted to the frame and normally located in parallelism therewith, one of said pair of beams having a sliding movement between stops on said third beam and the other of said pair of beams having a sliding movement between stops on said frame, substantially as described.

4. In a body dumping vehicle, the combination of a main frame, a body, a pair of oppositely extending beams pivoted to the front and rear ends respectively of the body, a third beam pivoted to the frame and normally located in parallelism therewith, one of said pair of beams having a sliding movement between stops on said third beam and the other of said pair of beams having a sliding movement between stops on said frame, and means permitting all of said beams to remain in parallelism during a lifting movement applied to the front end 55 of said body, whereby the body is tilted on a pivot at its rear end, substantially as described.

5. In a vehicle body dumping device, the combination with the vehicle frame of a body, a beam pivoted at the rear end of the

frame and normally extending forwardly in parallelism with the frame, means for disengageably connecting said beam to the frame, an elevating beam pivoted to the rear of the body and slidably engaging the 70 first mentioned beam, an elevating and tilting beam pivoted to the front end of the body and slidably engaging the frame, a fulcrum at the intersection of said elevating and elevating and tilting beams, and means 75 for adjusting said fulcrum longitudinally of one of said beams, substantially as described.

6. In a dumping vehicle, the combination of a main frame, a body, a pair of oppositely extending beams each thereof having a sliding bearing between stops on said frame, a sliding fulcrum at the intersection of said beams, and means for applying a lifting force to the body in such manner that 80 the body is caused to be first raised while being maintained in a horizontal position and then tilted, substantially as described.

7. In a dumping vehicle, the combination of a main frame, a body, a beam extending 90 from the front of the body to the rear of the frame, a second beam extending from the rear of the body toward the front of the frame, both said beams slidably engaging the frame, stops for limiting the sliding 95 movement, a fulcrum at the intersection of said beams, said fulcrum being fixed relative to said second beam and slidably relative to the first beam, and means for applying a lifting force to the body whereby said 100 second beam is first caused to slide on the frame and then said first beam is caused to slide, substantially as described.

8. In a dumping vehicle, the combination of a main frame, a body, a beam extending from the front of the body to the rear of the frame, a second beam extending from the rear of the body toward the front of the frame, both said beams slidably engaging the frame, stops for limiting the 105 sliding movement, a fulcrum at the intersection of said beams, said fulcrum being fixed relative to said second beam and slidably relative to the first beam, and means for so lifting said body that said second 110 beam is caused to slide on the frame before sliding movement of the first beam on the frame begins, substantially as described.

9. In a dumping vehicle, the combination of a main frame, a body, a beam extending 120 from the front of the body to the rear of the frame, a second beam extending from the rear of the body toward the front of the frame, both said beams slidably engaging the frame, stops for limiting the sliding 125 movement, a fulcrum at the intersection of said beams, said fulcrum being fixed relative to said second beam and slidably relative to the first beam, and means for so lifting said body that said second beam is 130

caused to slide on the frame, and during such sliding movement the slidable end of the first beam remains stationary whereby the body is elevated while remaining in substantially a horizontal position, substantially as described.

10. In a dumping device, the combination of a main frame, a body, a pair of beams forming the connection between the frame and body, both said beams having a sliding bearing between stops on the main frame, a fulcrum at the intersection of said beams, said fulcrum being slidably held on one beam and adjustably held on the other beam, whereby the body may first be raised while in a horizontal position, the extent of horizontal elevation depending on the adjusted position of said fulcrum, substantially as described.
15. In a dumping device, the combination of a frame, a body, a pair of slidably connected beams forming a connection between the body and frame, means associated with the beams, the body and the frame for effecting the elevation of the body while maintaining the same in substantially a horizontal position, and means for rendering said beams inoperative to perform their stated functions whereby the body may be tilted without elevation, substantially as described.
20. 11. In a dumping device, the combination of a frame, a body, a pair of slidably connected beams forming a connection between the body and frame, means associated with the beams, the body and the frame for effecting the elevation of the body while maintaining the same in substantially a horizontal position, and means for rendering said beams inoperative whereby the body may be tilted without elevation, substantially as described.
25. 12. In a dumping device, the combination of a frame, a body, a pair of slidably connected beams forming a connection between the body and frame, means associated with the beams, the body and the frame for effecting the elevation of the body while maintaining the same in substantially a horizontal position and for thereafter tilting the body, and means for rendering said

30. 13. In a dumping device, the combination of a frame, a body, a pair of slidably connected beams forming a connection between the body and frame, means associated with the beams, the body and the frame for effecting the elevation of the body while maintaining the same in substantially a horizontal position and for thereafter tilting the body, and means for rendering said

35. 14. In a dumping device, the combination of a frame, a body, a pair of slidably connected beams forming a connection between the body and frame, means associated with the beams, the body and the frame for effecting the elevation of the body while maintaining the same in substantially a horizontal position, and means for adjusting the connection between the beams whereby the extent of horizontal elevation may be changed, substantially as described.

40. 15. In an elevating and dumping device, the combination of a frame, a body, a pair of connecting beams, both thereof having a sliding bearing on the frame, a fulcrum at the intersection of the beams, means for applying a lifting force to the body in such manner that one beam slides on the frame to the limit of its movement before the other beam begins its sliding movement, whereby the body is elevated horizontally during the period of the sliding movement of the first mentioned beam, substantially as described.

45. of a frame, a body, a pair of slidably connected beams forming a connection between the body and frame, means associated with the beams, the body and the frame for effecting the elevation of the body while maintaining the same in substantially a horizontal position, and means for adjusting the connection between the beams whereby the extent of horizontal elevation may be changed, substantially as described.

50. 16. In a dumping device, the combination of a frame, a body, a pair of slidably connected beams forming a connection between the body and frame, means associated with the beams, the body and the frame for effecting the elevation of the body while maintaining the same in substantially a horizontal position, and means for adjusting the connection between the beams whereby the extent of horizontal elevation may be changed, substantially as described.

55. 17. In a dumping device, the combination of a frame, a body, a pair of slidably connected beams forming a connection between the body and frame, means associated with the beams, the body and the frame for effecting the elevation of the body while maintaining the same in substantially a horizontal position, means for adjusting the connection between the beams whereby the extent of horizontal elevation may be changed, and means for rendering said beams inoperative to perform their stated functions whereby the body may be tilted without elevation, substantially as described.

60. 18. In an elevating and dumping device, the combination of a frame, a body, a pair of connecting beams, both thereof having a sliding bearing on the frame, a fulcrum at the intersection of the beams, means for applying a lifting force to the body in such manner that one beam slides on the frame to the limit of its movement before the other beam begins its sliding movement, whereby the body is elevated horizontally during the period of the sliding movement of the first mentioned beam, substantially as described.

65. Signed at Chicago, in the county of Cook and State of Illinois, this 10th day of July, 1918.

GEORGE L. HARVEY
